UNITED STATES PATENT OFFICE.

JAMES M. POE AND STEELE C. FUGATE, OF VIOLA, ILLINOIS.

CRUPPER.

SPECIFICATION forming part of Letters Patent No. 240,180, dated April 12, 1881.

Application filed February 12, 1881. (No model.)

To all whom it may concern:

Be it known that we, JAMES M. POE and STEELE C. FUGATE, citizens of the United States, resident at Viola, in the county of Mercer and State of Illinois, have invented certain new and useful Improvements in Cruppers; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification, in which—

15 Figure 1 is a perspective view. Fig. 2 is a sectional view. Fig. 3 is a view of the blank. Our invention has relation to cruppers for saddles or harness; and it consists in the novel construction of the crupper of sole-leather 20 by pressing or clamping, all as hereinafter shown and described.

In the accompanying drawings, the letter *a* designates the outer leather, and *b* the filling. The outer leather is cut of sole-leather, in the 25 form shown at *c* in blank, having the attaching ends *d*, necks *e*, and central enlarged portion, *g*, one side of which is extended somewhat to form a roll edge. This blank is pressed or clamped into form over the tapering filling 30 *b*, in such a manner that the edge *h* will be

rolled upward at the back and within the edge of the upper portion, *k*, which extends downward over the same, forming a compact crupper without a seam.

This sole-leather crupper takes a better polish than those commonly formed of harness-leather, and requires no seam, the leather holding itself to form after the pressing or clamping operation. It will present a glassy surface to the flesh of the horse, and is not liable to gall or irritate. It also adds to the appearance of a harness. 35 40

Having described this invention, what we claim, and desire to secure by Letters Patent, is—

A sole-leather crupper consisting of a filling, *b*, and the outer leather, *a*, having the attaching ends, necks, and central enlarged portion, whereof the edge *h* of the lower portion extends under the covering-edge of the upper 45 50 portion, *k*, which extends downward at the back, the whole being pressed or clamped into form, substantially as specified.

In testimony whereof we affix our signatures in presence of two witnesses.

JAMES M. POE.
STEELE C. FUGATE.
